UNITED STATES PATENT OFFICE.

SILAS H. HAMILTON, OF LAWRENCE, KANSAS, ASSIGNOR, BY MESNE ASSIGNMENTS, TO HENRY W. PORTER, OF CHICAGO, ILLINOIS.

MANUFACTURE OF PAPER BOARDS.

SPECIFICATION forming part of Reissued Letters Patent No. 10,387, dated September 25, 1883.

Original No. 269,785, dated December 26, 1882. Application for reissue filed September 6, 1883.

DIVISION B.

To all whom it may concern:

Be it known that I, SILAS H. HAMILTON, of Lawrence, in the county of Douglas, and in the State of Kansas, have invented certain new and useful Improvements in the Manufacture of Paper Boards; and I do hereby declare that the following is a full, clear, and exact description thereof, reference being had to the accompanying drawings, making a part of this specification, in which—

Figure 1 is a perspective view of my improved board, a portion of one edge being broken to show the manner of combining the sheets; and Fig. 2 is a cross-section of the same.

Letters of like name and kind refer to like parts in each of the figures.

The design of my invention is to render practicable the employment of paper for purposes to which wood, metal, or stone has heretofore been applied; and to this end it consists in an improved article of manufacture, composed of a board formed of several sheets of paper saturated with resin and oil, then 25 coated with a solution of milk-curd and lime, and finally passed through heated pressure-rollers, substantially as and for the purpose hereinafter specified.

In the use of my invention I take sheets 30 of paper A—preferably made from straw or cane—and pass the same through a heated solution of resin and oil—preferably linseed or paraffine—in the proportion of two hundred and eighty pounds of resin to two gallons of oil, after which said sheets are permitted to remain until dry. I next coat one side of sheet A, except that intended for the lower side of the board, with a mixture of milk-curd and slaked lime, in the proportion of three parts of

milk-curd to one part of lime, after which 40 said sheets are passed between heated rollers and subjected to a heavy pressure, which causes them to adhere together and to form a board, B, that has any desired thickness or size. After the board B has been formed as 45 described, it is placed within a press and subjected to a moderate pressure until thoroughly cool, when it is ready for use.

The board thus constructed is thoroughly homogeneous, is entirely unaffected by water 50 or dampness, is in a great degree fire-proof, and possesses greater density, strength, and durability than is possessed by any of the woods ordinarily used for building purposes.

Having thus fully set forth the nature and 55 merits of my invention, what I claim as new is—

1. As a new article of manufacture, a paper board which consists of several sheets of paper-stock cemented together under heat and 60 pressure, so as to form a dense, strong, and durable plank for building purposes, substantially as described.

2. As a new article of manufacture, a board composed of several sheets of paper saturated 65 with resin and oil and united together by heat and pressure, substantially as described.

3. An improved article of manufacture, consisting of a board composed of several sheets of paper saturated with resin and oil, then 70 coated with a solution of milk-curd and lime, and finally passed through heated pressure-rollers, substantially as and for the purpose specified.

SILAS H. HAMILTON.
